UNITED STATES PATENT OFFICE.

JAMES WHITELAW, OF ST. LOUIS, MISSOURI.

SEWING-MACHINE WORK-HANDLING MECHANISM.

1,239,239.

Specification of Letters Patent. Patented Sept. 4, 1917.

Original application filed November 24, 1913, Serial No. 802,732. Divided and this application filed June 26, 1916. Serial No. 105,799.

To all whom it may concern:

Be it known that I, JAMES WHITELAW, a citizen of the United States, residing at St. Louis, and State of Missouri, have invented certain new and useful Improvements in Sewing-Machine Work-Handling Mechanism, of which the following is a specification.

My invention relates to sewing machine work handling mechanism and in some of its features more particularly to blind stitch sewing machines.

The general object of my invention is to provide a simple and efficient feed and plunger mechanism, and operating means therefor, for coöperation with a stationary presser foot to present portions of the work to be stitched in a presser foot opening, holding the goods at the time of such presentations snug and taut around the bender and handling the work uniformly and with certainty under high speed conditions.

Another object of my invention is to provide a simple and effective construction enabling the moving parts of the work-handling mechanism all to be displaced from normal position, so as to permit insertion or removal of work, at any time in the cyclic operation of the parts.

In the drawings wherein I have illustrated an embodiment of my invention—Figure 1 is a front elevation of a blind stitch sewing machine, with parts of the frame broken away to expose the work handling mechanism;

Fig. 2 is a section on line 2—2 of Fig. 1;

Fig. 3 is an enlarged end view of the work handling mechanism and associated presser foot parts;

Fig. 4 is a section on line 4—4 of Fig. 3;

Fig. 5 is a cross section on line 5—5 of Fig. 1;

Fig. 6 is a detail of the feed-length controlling cam;

Fig. 7 is a section of the plunger shaft on line 7—7 of Fig. 1;

Fig. 8 is a section on line 8—8 of Fig. 4; and

Fig. 9 is a section on line 9—9 of Fig. 3.

The blind stitch sewing machine shown in the drawing has a frame 10 comprising the upper and lower arms 11 and 12, an intervening post or standard 13 and in general provides suitable stitch forming mechanism 14 herein shown as of the chain stitch

type involving a curved reciprocating needle 15 and a complementary looper mechanism 16, both arranged to work above a stationary presser foot 18 which has therein an appropriate aperture 19 through which the goods may be presented to the needle. With the character of the stitch forming mechanism, the present invention is not concerned, but a stitch forming mechanism, of which fragments are illustrated in Fig. 1 is specifically shown and described in my copending application, Serial No. 802,733, filed November 24th, 1913, which on July 11th, 1916, matured into Patent No. 1,190,833. The present application is a division of my copending application, Serial No. 802,732 entitled "Sewing machine work handling mechanism" filed November 24th, 1913, which on September 19th, 1916, matured into Patent No. 1,198,800.

20 is a main shaft extending through the upper arm 11 of the machine and driven by the hand wheel pulley 21, said main shaft serving to actuate the stitch forming mechanism and having operating connections 80 through mechanism contained within the post 13 with the work handling mechanism carried by the lower arm 12. The lower arm 12 is hollow from its juncture with the post 13 to an integral end block or head 85 22 preferably arranged slightly out of alignment with the presser foot 18 so that mechanism supported outside of said block 22 may aline with the presser foot, a detachable cover 23 secured on the block 22 by screw 90 24 may inclose the space in which the working parts move.

The goods handling mechanism, generally indicated at 25, comprises in the specific construction shown a feed dog 26 to coöperate with the under side of the presser foot, a clamp member 27 coördinated with said feed member and also coöperating with the under side of the presser foot 18 and a plunger 28 coöperating with the aperture 19 of the presser foot 18 to present a bend in the goods therethrough to the operation of the needle, with actuating connections and regulating devices for these parts.

A feed dog 26 shaped to provide separated side points 26' receives a 4-way motion to perform its effective feeding operation by moving toward the rear of the machine. Specifically dog 26 has a rearward, substantially horizontal extension 30 pivot-

ally connected as at 31 with a substantially vertical crank 32 which is fast on a driving rock shaft 33, the rocking of which in a horizontal direction contributes the forward 5 and backward motions to the feed. For elevation and depression, the feed member has a connection between its ends as at 34 to a substantially vertical link 35, said link 35 pivotally connected as at 36 between the 10 ends of a lever 37, one extremity of which is pivotally connected as at 38 to a generally-horizontal crank arm 39 carried by a rock shaft 40, so that the rocking of the shaft elevates and depresses the crank arm 15 39 and with it the attached end of the lever 37. The remote end of said lever 37 is pivoted as at 41 to a link 42 suspended from a pivot 43 which, I prefer, shall receive support from a vertically movable carrier. Dis- 20 regarding possible movement of the suspension point 43 it will be obvious that rocking of the shaft 40 serves to elevate or depress the feed dog 26 with lever 37 working on 41 as a fulcrum and by appropriate 25 timing of the rocking operations of shafts 33 and 40, the feed part may be made to effect its desired 4-way cycle of movement. The clamp member 27, is preferably 30 formed with a short head serrated trans- versely as shown in Fig. 4 and disposed be- 35 tween two tooth points 26' of the feed dog 26, so as to work in a central slot of said feed dog. Said clamping head is intended, in the normal working operation, to clamp 40 the goods against the under side of the presser foot during the time when the feed dog is out of engagement with the goods and to be removed from holding position when the feed dog is exerting its feeding in- 45 fluence. To this end the clamp member and feed dog are inter-related for appropriate coöperation controlled by the operating mechanism for the feed dog. The clamping head 27 is carried by a vertical post 45, 50 sliding against head 22 and having guiding wings 46 at its sides working in grooves made therefor in the retaining plates 47, said sliding post constituting a carrier affording a bearing for the pivot 43 on which the link 42 is suspended.

I provide in conjunction with the mechanism described means normally to hold the post 45 in raised position but to effect its depression at will. Specifically I provide a 55 rod 50 extending along the front of the machine through a suitable bearing 51 near the juncture of the arm 12 and post 13 and through a bearing in the said block 22, and on the extremity of said arm I provide a 60 finger 53 engaging in a recess 54 provided therefor in the outer face of the post 45. This rod is appropriately provided at its 65 other end with a lever 56 to which the customary "kneelift" may be attached and said lever is acted on by a spring 57 normally

tending to rotate the rod 50 and through the finger 53 to lift the post 45.

The relation of the parts and the throw of the rock shaft 40 are such that the downward sweep of crank 39 when the feed dog 70 has completed its feeding movement, causes lever 37 to fulcrum on pivot 41 and through link 35 to retract the feed dog from the presser foot, but when the feed dog is raised, by the upward sweep of the crank 75 39, for commencement of the feeding action of the dog, said feed dog comes in contact with the under side of the presser foot before the throw of crank 39 is completed and then the lever 37 fulcrumming on the pivot 80 36 acts as a lever of the first class to draw downward upon the link 42 thereby withdrawing the clamp 27 from engagement with the under side of the presser foot or with the work, as best shown in Fig. 8. 85

The link arrangement shown permits the post 45 to be lowered, depressing the substantially vertical link 42 and thereby drawing down the link 35 and the feed dog 26 to a point where the feed dog and clamp mem- 90 ber are both withdrawn from the presser foot sufficiently for insertion of the work between the feed and clamp parts and presser foot. When so withdrawn, operation of the machine to actuate the rock shaft 95 causes the feed dog to go through an idle or useless 4-way motion but it will be apparent that by this arrangement the withdrawal of the feed dog and clamp from the presser foot to permit insertion of the work may be 100 effected while the machine is running, if desired, at any part of its cycle of operation.

The plunger 28 is carried by and bodily moves with the post 45, but may move a limited distance with respect to said carrier or 105 post 45. Specifically the plunger 28 is a cylindrical stem bearing at its upper extremity a properly shaped head 60, shaped to form a ridge in the goods transverse to the path of the needle, and at its lower end 110 having an enlargement or base 61. Said stem fits within an appropriate bore 62, in the post 45, and is normally depressed by a spring 63 acting between an upper shoulder of the bore and the base 61 to force said 115 plunger down into the post to the full extent permitted by the play at pin 64 carried by the stem within a slot 65, cut in the upper portion of the post 45. The lower end of the plunger base 61 projects below the 120 post 45 to such distance that in the normal operation of the device full elevation of base 61 of the plunger may project head 60, against the tension of spring 63, to a sufficient height to present a node of goods 125 through the presser-foot opening 19 to the needle.

For actuating the plunger to give it its movements relative to the clamping post 45 which carries it, I provide the rocking shaft 130

66 extending longitudinally of the frame, and bearing on its extremity a crank arm 67, the extremity of which, acting against the plunger base 61 to elevate the plunger, preferably carries a pin 68 extending longitudinally of the machine into a recess 69 provided therefor in the end-block 22, the range of throw of said crank arm 67 being regulable by an adjusting screw 70 extending from an exposed position upon the arm down through the end-block 22 into recess 69 to form an adjustable stop for pin 68.

It will be understood that the several rock-shafts are 33, 40 and 66, operated in appropriate timed relation by mechanism at the rear end of the machine, driven by the main shaft, and as has heretofore been stated the cyclic operations of the two rock-shafts 33 and 40 are not interfered with at all by the movement of the feed and clamp-mechanism from normal position to depressed position for goods-insertion. The rock-shaft 66 tends in its normal operation invariably to raise the plunger stem to a predetermined position, but I prefer that this elevating action shall be permitted by the plunger only when the cloth holding and feed mechanism are in normal relation to the work, the movability of the plunger with respect to the post 45 being limited by the extent of projection of base 61 of the plunger from the bottom of the post. In order, therefore, that parts may not be broken when extra heavy work is inserted or when the feed-dog and clamp-post are depressed by the operation of lever 56 while the machine is running, the driving connections with the plunger operating crank 67 of the driving gearing should include a yielding part and I prefer that the shaft 66, intermediate its ends, be flattened as at 66' (Fig. 7) so that said shaft may operate as a strong torsion-spring. Thus, although positive rocking movement is imparted to the rear end of shaft 66, when its crank-arm 67 encounters the bottom of clamp post 45 while the latter is depressed below normal position the torsion-spring action of the shaft 66 yields under the opposing power and resistance and prevents breakage of the parts, the plunger not being raised far enough to prevent goods-insertion.

The three shafts 33, 40 and 66, are all preferably driven by eccentrics on the main shaft. The rocking motion of shaft 33, which imparts the fore-and-aft motion to the feed dog 26 should be variable in order that the feed between stitches may be varied, and to this end I provide means for adjustment of the throw of the eccentric, on the main shaft, which operates the rock-shaft 33. Specifically 80 indicates a disk on the main shaft 20 secured thereon as by screws 81, said disk having in its face a slide-way 82, in which is mounted a slide 83, extend-

ing diametrically across the face of the disk, having a central opening 84 surrounded by a cam annulus 85 which, by adjustment of the plate transversely of the disk, may be thrown to different degrees of eccentricity 70 to the shaft 20. The plate 83 is retained in its slide-way on the disk by engagement of the notch 86 in the edge of the plate under the head of the screw 87 carried by the disk, and for diametric adjustment of 75 the plate I provide at one edge of the plate a flange 83' overhanging and bearing upon a pair of springs 88 which are seated in a recess made to receive said flange 83' in the edge of the disk, said plate being adjustable against the tension of the springs 88 by a screw 89 extending through the flange 83' and into the body of the disk. Manifestly by adjustment of the screw 89 the eccentricity of the annulus 85 may be varied. 85 The eccentric annulus 85 is engaged by an eccentric strap 90 carried by an arm 91 which makes pivotal connection as at 92 with a crank 93 on the shaft 33.

As the throw of the rock shaft 40 which 90 raises and lowers the feed need not be varied an ordinary eccentric 95 on the main shaft 20 may be employed in conjunction with the eccentric strap 96 carried by arm 97 which has pivotal connection 98 with the 95 crank 99 secured to shaft 40. As has heretofore been pointed out variation in the throw of the plunger may be taken care of by the resiliency of the torsional shaft 66, and, therefore, I may employ to actuate 100 said shaft 66 an ordinary eccentric 100 cooperating with the eccentric strap 101 carried by arm 102. In lieu of direct connection of said arm 102 with the crank arm 103 of the shaft 66, however, I prefer to 105 employ an intermediate bell-crank lever 104, pivoted as at 104' to the frame, having one arm pivotally connected as at 105, to the arm 102 and its other arm pivotally connected as at 106 to a link 107 which is in 110 turn pivoted to the crank 103. The relation of these parts is preferably such that as the eccentric is passed over dead-center with respect to its arm 102 the bell-crank 104 is thrown to approximately its upper 115 dead-center with respect to its link 107 so that the crank 103 on the shaft 66 is elevated to its maximum extent and held in such elevated position, so as to hold the plunger at substantially its highest position, for a material length of time in the cycle of rotation of the main shaft. This insures the maintenance of the plunger in elevated position for a sufficient length of time to give adequate opportunity for the 120 needle to penetrate the goods to be stitched, which are supported on the tip of the plunger, before the shaft 66 is rocked to withdraw the plunger-actuating crank 67 and permit the spring 63 to return the plunger 130

- to its lowest position within its carrying clamp-post. Also by properly proportioning the parts an extended range of motion may be given to the rock-shaft so that the 5 lever 67 when withdrawn will be thrown clear out of the way of the plunger-base 61 so as to not interfere with the full depression of the feed dog and the clamp-head carrying with it the plunger.
- 10 While I have herein described in some detail a specific embodiment of my invention, it will be apparent to those skilled in the art that changes might be made in the structure without departing from the spirit 15 of my invention and within the scope of the appended claims.
- Having described my invention, what I claim is:—
1. A sewing machine work-handling mechanism, comprising a work-handling plunger, and means to operate said plunger including a torsionally yielding shaft.
  2. A sewing machine work-handling mechanism comprising, in combination, a plunger, a movable part carrying said plunger and with respect to which said plunger has a limited range of movement, and operating means for said plunger including a torsionally yielding shaft.
  3. A sewing machine work-handling mechanism comprising, in combination, a plunger, means for varying the limit of throw of said plunger, an operating means for said plunger tending to raise the same to a variable position, said operating means comprising a torsionally yielding shaft.
  4. A sewing machine work-handling mechanism, the combination with a presser foot, of a feed member, a clamp member, a plunger carried by and movable with respect to said clamp member, yielding means normally pressing said clamp member toward the presser foot, means for imparting fore-and-aft movement to said feed, means for vertically moving alternatively the feed and clamp member comprising a power-applying part, a lever acted upon by said power-applying part having connection with both the feed and clamp member whereby either 50 of the latter may form an abutment against which the lever may act to move the other, and means for imparting movement to the plunger to move it with respect to the clamp.
  5. In a work-handling mechanism for blind-stitch sewing machines, the combination with a relatively stationary presser foot of a feed dog, a clamp coöperating therewith against the presser foot, a plunger 60 carried by and bodily movable with said clamp, means for operating the feed dog and clamp arranged to permit their depression out of normal position during the operation of said operating means, and means for moving said plunger with respect to the

clamp yieldable to accommodate the variations in bodily position of the plunger caused by said abnormal positions of the clamp.

6. In a work-handling mechanism for blind-stitch sewing machines, the combination with a relatively stationary presser foot, of a feed dog, a clamp coöperating therewith against the presser foot, a plunger carried by and bodily movable with said clamp, means for operating the feed dog and clamp arranged to permit their depression to abnormal position during the operation of said operating means, and means for moving said plunger with respect to said 70 clamp comprising a rock-shaft torsionally resilient to accommodate bodily displacement of said plunger incident to the depression of the clamp.

7. In a sewing machine, the combination with a relatively stationary presser foot having a work opening therein, a dog below said presser foot, a vertically movable clamp embraced by said feed dog, resilient means normally raising said clamp for coöperation 85 with the presser foot, a rock-shaft provided with a crank having a fore-and-aft movement, pivotally connected with the feed dog, a rock-shaft provided with a crank having an up-and-down movement, a horizontal lever connected with the last said crank, links pivotally connected with said lever and to the feed-dog and clamp respectively, and manual means for depressing said feed dog and clamp; whereby said feed dog and 90 clamp alternately coöperate with the presser foot each alternately providing the abutment against which said horizontal lever may act to depress the other, and whereby both the feed dog and clamp may be moved 100 to depressed position without interfering with the cyclic operation of the shafts.

8. In a machine of the character described, the combination with a presser foot, of work-handling means comprising in combination a feed dog, a vertically movable clamp, and a plunger within said clamp, said plunger bodily carried by said clamp and movable with respect thereto for projection above the clamp when the latter is in 110 contact with the presser foot, two inflexible rock shafts working on fixed axes, connections between said shafts and the feed dog and clamp for imparting 4-way cyclic movement to the dog and permitting the dog to 115 move with the clamp into operative or into inoperative planes, and means for operating said plunger with respect to said clamp comprising power applying devices and a yielding connection between the power applying devices and said plunger.

9. In a machine of the character described, the combination with a presser foot, of complementary work-handling means comprising in combination a feed dog, a vertically mov- 120

- able clamp, and a plunger extending through said clamp, bodily carried by said clamp and movable with respect thereto for projection above the clamp when the latter is in contact with the presser foot, two inflexible rock shafts working on fixed axes, connections between said shafts and the feed dog and clamp for imparting 4-way cyclic movement to the dog and permitting the dog to move with the clamp into operative or inoperative planes and means for operating said plunger with respect to said clamp, comprising a torsionally yielding rock-shaft for actuating the plunger. 65
- 10 10. In a machine of the character described, work-handling mechanism comprising a part movable between limits normally in one position, means for moving it bodily to abnormal position, and a torsionally yielding rock-shaft for imparting movement to said part in its normal position, yielding to accommodate its maintenance in abnormal position. 70
- 15 11. In a machine of the character described, the combination of a presser foot and complementary work handling mechanism comprising a feed dog, a clamp, means for moving said feed dog and clamp alternately toward and from the presser foot, a plunger carried by the clamp for movement therewith and movable with respect thereto, and means for moving said plunger with respect to the clamp. 75
- 20 12. In a sewing machine, work handling mechanism comprising in combination a clamp, means for operating said clamp, a plunger bodily carried by and movable with said clamp, and also movable with respect to said clamp, a spring interposed between said plunger and clamp, and means for moving said plunger with respect to said clamp against the tension of said spring. 80
- 25 13. In a sewing machine, work handling mechanism comprising in combination a plunger, means for operating said plunger comprising a torsionally yielding shaft and a crank on said shaft coöperating with said plunger, and adjusting means for limiting the throw of said crank. 85
- 30 14. A sewing machine work handling mechanism, comprising, in combination with a frame, a reciprocable plunger, a crank for operating said plunger, a torsionally yielding shaft for operating said crank, and an adjusting screw for adjustably limiting the throw of said crank, extending through said frame to exposed position upon the frame. 90
- 35 15. In a blind stitch sewing machine, the combination with a presser foot, of a member working toward and from the presser
- foot to coöperate therewith in handling the goods, means to move said member, a plunger carried by said member and movable therewith and means for moving said plunger with respect to said member. 95
- 40 16. In a blind stitch sewing machine, the combination with a presser foot, of a member working toward and from the presser foot to coöperate therewith in handling the goods, means to move said member, a plunger carried by said member and movable therewith and means for moving said plunger with respect to said member, tending to elevate said plunger to predetermined position regardless of the position of said member. 100
- 45 17. In a sewing machine the combination with a presser foot, of a member movable toward and from said presser foot to coöperate therewith, means for so moving said member, a plunger carried by and movable with said member and movable with respect to said member to project therefrom through the presser foot, yielding means normally holding said plunger in depressed position with respect to said member, and means for elevating said plunger above said member while said member is elevated. 105
- 50 18. In a sewing machine the combination with a presser foot, of a member movable toward and from said presser foot to coöperate therewith, means for so moving said member, a plunger carried by and movable with said member and movable with respect to said member to project therefrom through the presser foot, yielding means normally holding said plunger in depressed position with respect to said member, and yielding means for elevating said plunger with respect to said member, while said member is depressed. 110
- 55 19. In a sewing machine the combination with a presser foot, of a member movable toward and from said presser foot to coöperate therewith, means for so moving said member, a plunger carried by and movable with said member and movable with respect to said member to project therefrom through the presser foot, yielding means normally holding said plunger in depressed position with respect to said member, and yielding means including a torsionally resilient rock shaft for elevating said plunger with respect to said member while said member is depressed. 115

In testimony whereof I hereunto set my hand.

JAMES WHITELAW.
